UNITED STATES PATENT OFFICE.

PHILIP SHERRER, OF CLEVELAND, OHIO.

CASK-PITCHING APPARATUS.

SPECIFICATION forming part of Letters Patent No. 606,396, dated June 28, 1898.

Application filed August 28, 1897. Serial No. 649,865. (No model.)

To all whom it may concern:

Be it known that I, PHILIP SHERRER, a citizen of the United States, residing at Cleveland, in the county of Cuyahoga and State of Ohio, have invented certain new and useful Improvements in Cask-Pitching Apparatus; and I do hereby declare the following to be a full, clear, and exact description of the invention, such as will enable others skilled in the art to which it appertains to make and use the same.

My invention relates to improvements in pitching apparatuses by means of which the interior of casks is coated with an adherent film of a suitable substance (preferably rosin) for preservation of the liquid stored or shipped therein.

The object of my improvement is to equip a pitch-kettle with such means and in such manner as to enable the placing of said kettle distant from the contrivances provided for the "pitching" proper, as a result more convenience and efficiency being had and the danger of setting buildings on fire being diminished, since the kettle can be placed outside of buildings. I attain this object in and by an apparatus constructed and arranged substantially as illustrated in the accompanying drawings, in which—

Figure 1 represents a plan view of said apparatus and appendages. Fig. 2 represents a vertical sectional view of the same; and Fig. 3 is a transverse sectional view on line $x-x$, Fig. 1.)

Like letters of reference denote like parts in the drawings and specification.

Substantially the apparatus comprises the kettle A, which is placed over a suitable fireplace B, a discharge-pipe C, drip-pan D, a series of branches leading from pipe C, and suitable barrel or keg supports E.

The kettle A is provided with a cover F, which is divided into the parts a, b, and c. Attached to the part a and depending into the kettle A is the pump G, the supply-pipe H of which terminates in a strainer J. (See Fig. 2.) The pump, as shown, is of the oscillating type, it being operated by means of the lever I, which extends through the cover and derives its motion by means of a crank connection with the wheel or pulley K'. (See

Figs. 1 and 2.) Adjacent the kettle in open relation with the furnace underneath same is a channel L, built of fireproof material, and said channel terminates in a flue or chimney M more or less distant from the fireplace B or kettle A. In and along the upper portion of said channel extends the discharge-pipe C, within the drip-pan D, which is in communication with the part b of the kettle-cover F 60 and the flue M.

The drip-pan D and plate or plates N establish in conjunction with the channel-walls d e the upper and lower smoke-flues f and g. At or near the beginning of said flues or close 65 to the fire-bridge h is hinged the gate O in such manner as to enable the closing of either one of the flues f and g for the purpose as hereinafter explained.

Each of the branches C' C'' of the pipe C is provided with a stop and waste cock P and a lever i with shifter i'. (See Fig. 3.) From the cocks extend the pipes Q, which terminate in a spray-nozzle K, the latter protruding above the keg-supports E. (See Figs. 2 and 75 3.) The supports E are placed over the top of the pan at suitable distance apart to enable convenient manipulation of the casks. Lids R are used intermediate said supports and over the entire surface of said pan, so 80 that the vapors within same can only escape through the chimney.

In placing a cask it is first set into the notch l for adjustment, so that the bung-hole thereof will fit over the nozzle K by simply 85 rolling the cask from notch l to l'.

The pump G is kept in continuous operation for supply of pipe C with hot pitch, and the pitch issues through the spray-nozzle upon moving the shifter out or inward, according 90 to how the plug of the cock is set. To avoid overpressure within pipe C, I provide a "waste branch" in connection with the cocks, and the waste from said cocks as well as the casks is caught in the drip-pan and conveyed 95 or returned to the kettle. The pan can be maintained in more or less heated condition by means of the gate O. If said gate closes the flue g, then all gases and smoke escape through flue f into the chimney. The gases 100 in coming in direct contact with the pan heat same to such extent that any water which

may run out the casks and into the pan is instantaneously converted into steam, which escapes through the chimney. Danger of explosions by reason of water reaching the kettle is thereby avoided. Should the pan become too hot, then the gate O is turned to shut out the flue f, and the smoke escapes through the lower flue g.

It is preferable to have perforations in the partition N, so that some of the hot gas may still reach the upper flue for the purpose of maintaining the pan in the requisite or normal heated condition.

From the foregoing it is obvious that the discharge-pipe C and appendages may be extended to accommodate a series of keg-supports, and also such contrivances may be used in connection with any kind of pitching-kettles without departing from the nature of my invention.

What I claim, and desire to secure by Letters Patent, is—

In a cask-pitching apparatus the combination with the kettle and a fireplace therefor, of a pipe leading from a pump within said kettle, said pipe being provided with a series of spray-nozzles, keg-supports arranged with regard to said spray-nozzles, a drip-pan under said pitch-conveying pipe and a divided controllable flue for heating said pan and leading the smoke from said fireplace all constructed and arranged substantially as and for the purpose set forth.

In testimony whereof I affix my signature in presence of two witnesses.

PHILIP SHERRER.
